UNITED STATES PATENT OFFICE.

DAVID RUTHERFORD ROSS, OF COBURG, VICTORIA, AUSTRALIA.

SUPERHEATER IN STEAM-BOILERS.

1,392,080.

Specification of Letters Patent. Patented Sept. 27, 1921.

Application filed June 19, 1920. Serial No. 390,087.

To all whom it may concern:

Be it known that I, DAVID RUTHERFORD Ross, a subject of the King of Great Britain, residing at No. 87 Munro street, 5 Coburg, in the State of Victoria, Australia, have invented certain new and useful Improvements in Superheaters in Steam-Boilers; and I do declare the following to be a full, clear, and exact description of the 10 invention, such as will enable others skilled in the art to which it appertains to make and use the same.

This invention relates to steam superheaters of the type comprising a header or 15 box divided into compartments that are in communication with each other through Field tubes which depend from the header or box in the path of the hot gases escaping from the flue tubes of a locomotive or other 20 boiler into the smoke box in which the superheater is located. The object of the invention is to provide an improved construction of such a superheater adapted to effect the 25 superheating more efficiently than in existing arrangements of the kind stated. For this purpose according to the invention the saturated steam inlet to the header, and the superheated steam outlet therefrom are located about midway of the length of the 30 header in substantially one common plane, as will be hereinafter more particularly described in conjunction with other features of the invention.

In the drawing Figure 1 illustrates in 35 sectional elevation a superheater according to the invention arranged in the smoke box of a locomotive.

Fig. 2 is an end view of the arrangement shown in Fig. 1, looking toward the smoke 40 box which, as regards the right hand half of the figure is shown in section.

Fig. 3 shows the superheater removed from the smoke box, in plan.

Figs. 4, 5 and 6 are vertical longitudinal 45 sections corresponding to the lines A—A, B—B, and C—C, respectively of Fig. 3.

Figs. 7 and 8, are horizontal sections corresponding to the lines D—D, and E—E, respectively of Fig. 4.

50 Figs. 9, 10 and 11 are vertical transverse sections corresponding to the lines F—F, G—G, and H—H, respectively of Fig. 3.

As will be seen from the drawings the superheater box or header is of elongated

rectangular shape in plan and it is constructed in two parts, namely a hollow upper part *a* the interior of which is divided by a longitudinal partition *b* and transverse partitions *c* into a compartment *d* that extends the full length of the header, and two end 60 compartments *e* between which is an intermediate compartment *f* that, as hereinafter described, is the final superheated steam compartment and is in free communication with a two-way branch *g* connected to the 65 right and left steam supply pipes *h*, leading to the cylinders on each side of the locomotive, or if the superheater be arranged in connection with a boiler of other type, the pipes *h* or a single pipe, would lead to the 70 engine or other place where the superheated steam is to be utilized.

The end compartments *e* of the box or header are in free communication through passages *k*, see Figs. 5 and 10, with an inlet branch *m* leading from the steam space above the water in the boiler *n*.

Transverse partitions or webs *o* downwardly extending from the bottom wall *p* of the upper part *a* of the header divide the 80 chamber formed by and between the said bottom wall and a plate *q*, that is suitably secured to the marginal flange of the part *a*, into a middle compartment *r* and two end compartments *t*. Through groups 1 of Field 85 tubes, the upper end compartments *e*, in communication with the common saturated steam inlet *m*, are placed in communication with the lower end compartment *t*, while the groups 2 of Field tubes place the said 90 lower end compartments *t* in communication with the long upper compartment *d*. The compartment *d* communicates by groups 3 of Field tubes with the central lower compartment *r* which by groups 4 of Field tubes 95 is placed in communication with the final superheated steam compartment *f* that is connected to the branch *g*. It will thus be seen that saturated steam entering the header flows first through the end compartments *e* 100 and then flows in series through the Field tube groups 1, 2, 3 and 4 and the corresponding compartments, the last group of tubes namely, group 4, being located centrally and nearest the flue tubes of the boiler 105 so that the final superheating is most intense.

In the example illustrated the superheater

is secured in place not only by bolts *u* that pass through the flange of the inlet branch *m* but also by bolts *w* that extend into the chamber *f* and the nuts of which are accessible through an opening normally closed by a door *x*, and bolts *y* that pass through bosses at the sides of the said inlet branch.

In practice, the Field tubes advantageously occupy about $\frac{1}{3}$ rd of the height of the smoke box, that is to say, about the middle third of the height thereof, so that the hot gases coming through the flue tubes of the boiler and immediately on leaving the latter, will impinge upon the Field tubes, and pass through and between the series or groups thereof to the chimney.

In this way the steam flowing between the inner and outer Field tubes becomes effectively superheated. In addition to the outer surfaces of the Field tubes directly receiving the heat, the header plate *q* from whence they depend will also be exposed to the heat waves, and will assist in keeping the compartments above in a similarly heated condition.

I do not confine myself arbitrarily to the arrangement of the compartments in regard to the groups of inlet tubes or outlet tubes but I have found by experiment that the number of compartments shown in the superheater illustrated may be used with satisfactory results. I have found by experiment that this arrangement will permit a total of several hundred of such tubes being employed.

I would point out that the superheater embodying my invention and arranged as shown in Figs. 1 and 2, acts as a deflector, so that a locomotive using it can dispense with the brick arch usually employed with other forms of superheaters. The invention also acts as a partial spark arrester, and the whole can be easily cleaned with a jet of dry steam or alternatively compressed air.

The superheater being placed behind the throttle valve insures superheated steam passing direct to the cylinders on the opening of such valve. The ends of the depending outer tubes are closed.

I claim:—

1. A steam super-heater comprising a body member in which there are tiers of compartments, one tier having end compartments and an intermediate compartment, together with a longitudinal compartment adjacent the aforesaid compartments, another tier having end compartments and a central compartment, and a plurality of tubes making connection from the end compartments in the said first tier thereof to the end compartments in the second tier thereof, then from the end compartments in the said second tier to the longitudinal compartment in the first tier, then from the said longitudinal compartment in the first

tier to the central compartment in the second tier, and finally from the central compartment in the second tier to the intermediate compartment in the first tier.

2. A steam super-heater comprising a body in which there are tiers of adjacent substantially parallel compartments, one tier having end compartments, a compartment intermediate of the end compartments and a longitudinal compartment adjacent the aforesaid compartments, while in the other tier there are end compartments and a central compartment, and a plurality of Field tubes making communication from the end compartments in the said first tier thereof to the end compartments in the second tier thereof, then from the end compartments in the said second tier to the longitudinal compartment in the first tier, then from the said longitudinal compartment in the first tier to the central compartment in the second tier, and finally from the central compartment in the second tier to the intermediate compartment in the first tier.

3. A steam superheater comprising a body in which there is provided an upper tier of compartments and a substantially parallel lower tier of compartments, the upper tier having end compartments, a compartment intermediate thereof and a longitudinal compartment adjacent the aforesaid compartments while the lower tier has end compartments and a central compartment, and a plurality of tubes making communication from the end compartments in the said first tier thereof to the end compartments in the second tier thereof, then from the end compartments in the said second tier to the longitudinal compartment in the first tier, then from the said longitudinal compartment in the first tier to the central compartment in the second tier, and finally from the central compartment in the second tier to the intermediate compartment in the first tier.

4. A steam superheater comprising a body having a saturated steam inlet and comprising a plurality of tiers substantially parallel and adjacent, the outer tier having end compartments, a compartment intermediate of the same and a longitudinal compartment adjacent the aforesaid compartments with the other tier having end compartments and a central compartment, the intermediate compartment in the first tier being a super heated steam compartment and having passages from the steam inlet leading over the same to the said end compartments in the first aforesaid tier thereof, there also being an outlet connection leading from the said super heated steam compartment, and a plurality of tubes making connection from the end compartments in the first tier to the end compartments in the second tier, from the end compartments in the sec-

ond tier to the longitudinal compartment in the first tier, from the longitudinal compartment in the first tier to the central compartment in the second tier and then from
5 the central compartment in the second tier to the intermediate or super heated steam compartment in the first tier.

In testimony whereof I have signed my name to this specification in the presence of two subscribing witnesses.

DAVID RUTHERFORD ROSS.
